PERFORATING GUN

Alexander A. Tauben, Bakersfield, Calif., assignor
to Bishop Oil Company, San Francisco, Calif.,
a corporation of California

Application June 17, 1942, Serial No. 447,380

6 Claims. (Cl. 164—0.5)

This invention relates generally to well working tools and more particularly to devices for perforating well casing to increase the yield of a well.

The primary object of the invention is to provide a perforating gun employing bullet cartridges for perforating casing in the well hole, the invention being structurally and functionally characterized by: (1) low cost of construction, and use of inexpensive ammunition permitting inexpensive exploration of upper and shallow strata having small yield, as compared to the use of devices heretofore proposed, whose complexity and attending high cost can be borne only by the operators of wells having large production, in contrast to which the tool embodying this invention can be profitably used by operators of wells producing heavy, low value crudes, and shallow wells which usually produce only one to five barrels per day, so that a one hundred percent increase in production would not justify the use of an expensive perforating device; (2) elimination of the expense of factory loaded barrel and cartridge units requiring a barrel for each cartridge, with the attending cost and maintenance of a large stock of expensive barrels, as well as the danger of transporting and handling such explosive units; (3) safe handling due to the fact that the barrels are field loaded and directly applied to the gun just prior to use, and cannot be discharged by pressure alone, but require percussion effected by a go-devil or other form of impact delivering means, and (4) extreme simplicity of its mechanism, low cost of replacement parts, and ease of inspection and repair.

With this and other objects in view, the invention resides in the combinations, arrangements and functional relationships of elements as set forth in the following specification and particularly pointed out in the appended claims.

In the accompanying drawings,

Figure 1 is a vertical longitudinal sectional view, partly in elevation, of one form of perforating gun embodying this invention;

Figure 2 is an enlarged fragmentary longitudinal sectional view of the perforating gun, with the mechanism thereof in normal or set position;

Figure 3 is a view similar to Figure 2 with the mechanism actuated to fire the gun;

Figure 4 is a transverse sectional view taken on the line 4—4 of Figure 2;

Figure 5 is a fragmentary view in elevation of a portion of the perforating gun, and show-

ing an operative connection embodied in the mechanism; and

Figure 6 is a transverse sectional view taken on the line 6—6 of Figure 2.

Referring specifically to the drawings, the invention in its illustrated embodiment is primarily intended for use under conditions in which firing into fluid is not necessary. The invention comprises a generally cylindrical body B having a main section 10, a nose piece 11 (Figure 1), and an intermediate section 12. The intermediate section has one open end seated against an annular shoulder 13 on the main section 10 and is detachably secured to the latter by means of a nut 14 threaded on a stud 15 projecting from the forward end of the main section and through an opening in a transverse partition 16 in the intermediate section. The intermediate section is prevented from turning on the main section by a pin 16a, and co-acts with the main section to define a spring chamber 17 between the partition 16 and the forward end of the main section. The nose piece 11 is detachably secured to the forward end of the intermediate section 12 by means of a fastening member 18.

The tail end of the main section 10 is provided with a cylindrical coaxial extension 20 in which is screwed the attaching stud 21 of a connector 22 on one end of a wire line 23 by which the perforating gun is lowered into a string of casing in a well hole and is suspended at the location desired for the perforating operation. The stud 21 is provided with a jam nut 24 by which the connector 22 is locked to the section 10.

At intervals along the length of the main section 10, are barrels 30, the bores 31 of which receive bullet cartridges 32. In the present instance three of the barrels are provided and are arranged in the body at a one hundred and twenty degree spacing as the body is viewed in transverse section and as indicated by the center lines a, b and c in Figure 4. The barrels 30 are of identical construction and each is externally threaded at 33 and is screwed into a radial pocket 34 in the section 10. The outer end of each barrel is provided with a wrench receiving head 35, and the outer end of each pocket 32 is of enlarged diameter as indicated at 36, to receive a socket wrench (not shown) in applying the wrench to the head.

For each barrel 30 a firing mechanism is provided, and each is arranged about the same radial center line a, b, or c as the respective mechanism. As the firing mechanisms are constructed iden-

tically in all essentials, a detailed description of one mechanism will suffice for all.

Each firing mechanism comprises a firing pin 37 reciprocably mounted in a radial bore 38 in the section 10 in center fire relation to the primer of a cartridge 32 in the respective barrel 30. The rear end of the firing pin 37 extends into a radial pocket 39 in the section 10, the outer end of which pocket is threaded to receive a closure plug 40. The rear end of the firing pin is bifurcated to receive one arm 41 of a bell-crank lever 42 pivoted on a pin 43 carried by spaced lugs 44 on a bracket 45 secured against the bottom wall of the pocket 39 by screws 46, and having an opening 47 through which the firing pin freely passes.

A cotter pin 48 spans the bifurcated portion of the firing pin and is adapted to be engaged by the arm 41 of the lever 42 to retract the firing pin in a manner to be later described. The other arm 49 of the lever 42 is interposed between coaxially related rods 50 and 51 reciprocably mounted in a longitudinal bore extending through the main section 10, with the outer end of the rod 51 located in the spring chamber 17 and having a stop collar 52 against which one end of a coil spring 53 abuts. The other end of the spring 53 receives a centering stud 54 and bears against the partition 16 so as to function in urging the rod 51 against the arm 41 to retain the firing pin 37 in the retracted position shown in Figure 2, and to urge the rod 50 to the extreme position shown in this figure, wherein the rod projects into an annular sealing chamber 55 formed in the rear end of the section 10 around the extension 20.

Reciprocably mounted on the extension 20 and having a head 56 bearing against the rods 50 of the three firing mechanisms in the chamber 55, is a plunger 57 broadly constituting an actuating element common to the several firing mechanisms. The plunger is provided with an annular shoulder 58 which co-acts with a retaining nut 59 screwed into the rear end of the body section to limit the upward movement of the plunger under the urging action of the springs 53 of the three mechanisms.

The plunger 57 has a tubular extension 60 screwed into the plunger and locked thereto by a nut 61. The extension 60 freely receives the wire line 23 and encloses the connector 22. Suitable packings 62 and 63 are provided on the plunger to seal the chamber 55 against the entrance of foreign substances. A sleeve 65 of waterproof canvas or other suitable flexible material is secured by a metal band 66 to the section 10, and by a second metal band 67 to the extension 20 to provide an additional means for protecting the enclosed parts against foreign substances.

The upper end of the plunger extension 60 is formed to provide an anvil or striking surface 68 and is adapted to be struck by a go-devil 69 or other weighted body freely receiving the wire line 23 and adapted to be dropped from the top of the well hole to strike the anvil 68 and simultaneously actuate the three firing mechanisms in the operation of the perforating gun which is as follows:

With the three barrels 30 loaded with bullet cartridges 32 and then screwed into the respective bores 34, the perforating gun is lowered by the line 23 into the well casing to the desired level for perforating the casing. With the gun suspended at such level, the go-devil 69 or other impact delivering mass is released from the top of the well so as to gravitate on the line 23 and strike

the anvil 68, thus driving the plunger 57 from its uppermost extreme position shown in Figure 3. This motion is directly transmitted to the rods 50 which rock the bell-crank levers 42 and project the respective firing pins 37 to strike the primers of the cartridges 32 and simultaneously fire the latter for perforation of the casing by the bullets of the cartridges. The compressed springs 23 immediately act to restore the parts to the position shown in Figure 2, for a repetition of the operation upon reloading the barrels after the gun is raised from the hole.

It will be clear that a greater or lesser number of gun barrels and co-acting firing mechanisms can be provided in the body B, and that the principle of the rods 50 and 51 with the interposed bell-crank levers could be utilized to provide for additional gun barrels and firing mechanisms at locations along the length of a longer body should it be desired to simultaneously perforate the casing at a greater number of points.

I claim:

1. A perforating gun comprising: a body adapted to be lowered into a well casing; a plurality of cartridge barrels arranged at intervals along the length of said body and at different locations circumferentially thereof to discharge cartridges in different directions laterally of the body; firing mechanisms, one for each of said barrels; each of said mechanisms including an actuating rod, with said rods arranged at circumferentially spaced locations in the body and parallel to the longitudinal axis thereof; and a plunger reciprocably mounted on the body and having an end bearing upon an end of each rod for movement thereof to actuate the firing mechanisms and simultaneously discharge said barrels when said plunger is struck.

2. A perforating gun comprising: a body adapted to be lowered into a well casing; a plurality of cartridge barrels arranged at intervals along the length of said body and at different locations circumferentially thereof to discharge cartridges in different directions laterally of the body; firing mechanisms, one for each of said barrels; each of said mechanisms including a firing pin, a bell-crank lever having one arm operatively connected to said pin, two actuating rods between which the other arm of the bell-crank lever is interposed, and a spring co-acting with one of said rods and with said lever to urge the other rod and the firing pin to an extreme position wherein the firing pin is retracted; and a plunger reciprocably mounted on said body and engaging said other rod of each of the firing mechanisms to actuate the latter by simultaneously projecting the firing pins thereof when said plunger is struck.

3. A perforating gun comprising: a body adapted to be lowered into a well casing; a plurality of cartridge barrels arranged at intervals along the length of said body and at different locations circumferentially thereof to discharge cartridges in different directions laterally of the body; firing pins, one for each barrel and mounted in the body to occupy projected and retracted positions; an actuating element reciprocably mounted on the body; actuating rods extending longitudinally of the body, with one for each firing pin and engaged by said element at different circumferentially spaced locations; means operatively connecting said rods to the respective firing pins to project the latter simultaneously when said element is struck; and

means for urging the firing pins to retracted position and said element to one extreme position through the medium of said rods.

4. A perforating gun comprising: a body adapted to be lowered into a well casing and having a gun barrel adapted to discharge a cartridge laterally of the body; a firing pin for said barrel; a bell-crank lever having one arm operatively connected to said pin; two actuating rods between which the other arm of said lever is interposed; a spring co-acting with one of said rods and with said lever to urge the other rod and the firing pin to one extreme position wherein the firing pin is retracted; and a plunger reciprocably mounted on said body and engaging said other rod to move the firing pin to cartridge-firing position when said plunger is struck by a go-devil released into the well casing.

5. A perforating gun comprising: a body having an extension at its upper end to which a line is connectible to lower the body into a well casing; the body having a sealing chamber around said extension; a plunger reciprocably mounted on said extension to extend into said chamber, and having an anvil adapted to be struck by a go-devil to move the plunger downwardly in the chamber; a gun barrel supported in the body for the discharge of a cartridge laterally thereof; a firing pin for said barrel; a bell-crank lever having one arm operatively connected to said pin; two actuating rods between which the other arm of said lever is interposed; a spring co-acting with one of said rods and with said lever to urge the other rod and the firing pin to one extreme position wherein the firing pin is retracted and said other rod projects into said chamber and engages said plunger to retain the latter against downward movement in the chamber.

and firing mechanism for said barrel including an actuating rod projecting into said chamber and engaged by the end of said plunger for movement thereby to actuate said mechanism and fire a cartridge in said barrel when said plunger is struck as aforesigned.

6. A perforating gun comprising: a body having an extension at its upper end to which a line is connectible to lower the body into a well casing; the body having a sealing chamber around said extension; a plunger reciprocably mounted on said extension to extend into said chamber, and having an anvil adapted to be struck by a go-devil to move the plunger downwardly in the chamber; a gun barrel supported in the body for the discharge of a cartridge laterally thereof; a firing pin for said barrel; a bell-crank lever having one arm operatively connected to said pin; two actuating rods between which the other arm of said lever is interposed; a spring co-acting with one of said rods and with said lever to urge the other rod and the firing pin to one extreme position wherein the firing pin is retracted and said other rod projects into said chamber and engages said plunger to retain the latter against downward movement in the chamber.

ALEXANDER A. TAUBEN.
